UNITED STATES PATENT OFFICE.

FRANK PIRRO DE NOBILI, DECEASED, LATE OF LOS ANGELES, CALIFORNIA, BY
FANNIE PIRRO DE NOBILI, EXECUTRIX, OF LOS ANGELES, CALIFORNIA.

PARCEL BOX.

Application filed March 24, 1921. Serial No. 455,283.

To all whom it may concern:

Be it known that FRANK PIRRO DE NOBILI, who was a subject of the King of Italy, and a resident in the city and county of Los Angeles, State of California, but who is now deceased, did invent new and useful Improvements in a Parcel Box, of which the following is a specification.

My invention relates to improvements in a parcel box and the object of my invention is to provide a device of this nature which is simple and inexpensive in construction, and in which provision is made to effectually prevent the unauthorized removal therefrom, or the destruction of or tampering with any object deposited therein, or its withdrawal through the inlet opening once the same has been deposited therein, and thus obviate the risk of theft or destruction of any object deposited therein, a possible occurrence in boxes not so provided.

I attain this object by the construction illustrated in the accompanying drawing in which—

Figure 1 is a front view of the entire parcel box, as the box appears when the door of the receiving chamber is open;

Figure 2 is a side view of the entire parcel box;

Figure 3 is a sectional view on x^3, x^2 , which shows interior parts in their position when the door of the receiving chamber is open;

Figure 4 is a plan view with cover of box removed, showing the revolving door turned to the position where the receiving chamber is open for the receipt of parcels;

Figure 5 is a plan view with cover of box removed, showing the revolving door turned to the mid position where all openings are closed; and

Figure 6 is a plan view with cover of box removed, showing the revolving door turned to the limit of its travel, where it has completed the depositing of goods in the delivery chamber.

Similar figures of reference indicate similar parts throughout the several views.

My parcel box consists of a suitably formed casing 1 of any desired shape, being shown substantially rectangular in the drawing, and it is closed on all sides and top and bottom, except for an opening in the front which is closed by a revolving door 2.

The front opening 15 is closed by a revolv-

ing cylindrical door 2, which consists of a circular floor 4 on which is erected a cylindrical wall 2^a continuous except for the opening 3. A circular top 5 is rigidly secured to the top of the wall 2^a through the distance 2^b, the remainder of it being unsupported as the wall 2^a is cut away to form the slot 2^c in which the lever 9 works. Floor 4 and top 5 are pivoted at their centers on bearings 6 and 7 attached to the bottom and top of the box respectively. A partition 11 extends from the floor 4 to the level of the bottom of slot 2^c. A swinging wall 8 pivoted to floor 4 and 14 and to the top of wall 2^a at 12 on the edge of the opening 3, swings in the receiving chamber 3^a between the partition 11 and the opening 3.

To the top of swinging wall 8 is secured the lever 9 which is pivoted at its outer end to lever 17 by the pin 10. The other end of lever 17 is pivoted to the top of the box by pin 18. The revolving door 2 is rotated by means of the handle 13 which passes through the slot 21 in the outer wall.

Figure 4 shows the door 2 with its opening 3 opposite the opening 15 in the front wall ready to receive goods. There is no communication in this position between the receiving chamber 3^a and the delivery chamber 16. By drawing handle 13 to the front and right the door 2 revolves to the position shown in Figure 5 where the opening 3 is entirely covered by the outer wall of the box 1^a. The opening 15 in the front of the box is also closed by wall 2^a of the revolving door, and the swinging wall 8 has begun its travel to the right. In this position there is no communication between any of the three spaces, namely, the outside of the box, the receiving chamber 3^a, and the delivery chamber 16.

Continuing to draw the handle 13 to the right further revolves the door 2 to the position shown in Figure 6 at the limit of its travel. Here the opening 15 is still closed by the wall 2^a of the revolving door, but the opening 15 is now entirely within the delivery chamber 16. The swinging wall 8 has now been turned out through the opening 3, sweeping before it all articles originally deposited in the receiving chamber when the door was in the position as shown in Figure 4. It is readily apparent that goods deposited in the receiving chamber 3^a when the door 2 is open as in Figure 4, will be trans-

ferred to the delivery chamber 16 when the door 2 is fully turned to the position shown in Figure 6 without at any time permitting access to be had from the outside of the box 5 to the delivery chamber 16.

Access to the delivery chamber 16 for the removal of goods can be had through the ordinary doors 19 and 20.

The essential elements of my invention 10 are: revolving door 2 complete including floor 4, wall 2^a, partition 11, swinging wall 8, and top 5, and levers 9 and 17. These features may be applied with equal facility to suitable openings in drawers, lockers, or any 15 other receptacle provided for the deposit therein of matter.

What I claim is:

A parcel box of the character described, having an inlet opening, a combination of a 20 revolving door with a handle, a circular floor, a circular top, a cylindrical wall, a cylindrical partition, a swingable wall, and two levers, the cylindrical wall being erected on the circular floor and circular top continuous except at the opening, the inner end at 25

the top of the swingable wall being extended into a lever and pivoted to this lever being another lever, the cylindrical partition extending from one side to the other side of the parcel box being located between the 30 front and back of the box, said cylindrical partition further extending to the top of the parcel box only leaving sufficient space for the operation of the lever extending from the swingable wall, the revolving door being rotated by means of the handle, drawing of the handle towards the front and right side of the box revolving the door, said movement of the door being caused through the action of the handle which causes an 35 automatic movement of the swingable wall completely including the two levers and closes the opening to the box, said swingable wall continuing to travel until the goods that have been placed in the receiving chamber 40 have been transferred to the delivery chamber from where the goods are abstracted through another door.

FRANK PIRRO DE NOBILI,
By Mrs. Fannie Pirro De Nobili, Executrix.
